Primary Examiner — Elizabeth Albert(74) *Attorney, Agent, or Firm* — Wolf, Greenfield & Sacks, P.C.; Randy J. Pritzker(57) **CLAIM**

The ornamental design for pen, as shown and described.

DESCRIPTION

FIG. 1 is a side, top, perspective view of a pen showing our new design;

FIG. 2 is a left side view thereof, the right side view being a mirror image of the left side view;

FIG. 3 is a top view thereof;

FIG. 4 is a bottom view thereof;

FIG. 5 is a front view thereof; and,

FIG. 6 is a rear view thereof.

The broken lines showing the proximal end button, clip and distal end of the pen in FIGS. 1-6 are included for the purpose of showing portions that-form no part of the claimed design.
